UNITED STATES PATENT OFFICE.

FESTUS S. RAND, OF PROVIDENCE, RHODE ISLAND, ASSIGNOR TO UNIVERSAL
WINDING COMPANY, A CORPORATION OF MAINE.

WINDING MACHINE.

1,027,277.

Specification of Letters Patent.

Patented May 21, 1912.

Application filed September 5, 1911. Serial No. 647,671.

To all whom it may concern:

Be it known that I, FESTUS S. RAND, a citizen of the United States, residing at Providence, in the county of Providence and 5 State of Rhode Island, have invented certain new and useful Improvements in Winding-Machines, of which the following is a specification.

My invention relates to winding machines 10 and particularly to machines for winding taper-ended, or pointed cops such as that shown and described in U. S. Patent No. 940,489, granted to Simon W. Wardwell, November 16th, 1909. In this style of machine the taper of the nose of the cop is 15 regulated by a former, so-called, which controls the position of the contact-wheel for regulating the disposition of the layers of winding in building up the heel of the cop. 20 The present invention consists particularly of improvements in the construction and arrangement of the former-devices whereby the former arm can be set to be adjustable; or, whereby it can be locked against 25 adjustment to prevent inexperienced operators from making incorrect adjustments.

The invention is fully described in the following specification, illustrated by the accompanying drawings, in which:—

30 Figure 1 is a plan view of the winding-spindle, traverse-bar and thread-guide showing the relation of the former-device thereto; Fig. 2, a longitudinal elevation of the same, looking in the direction indicated by the arrow *q*, Fig. 1, and showing the 35 traverse-mechanism for the thread-guide and driving gears for the winding-spindle; Fig. 3, an enlarged plan view of the former-device and a portion of the traverse-bar, with 40 the latter shown partly in section; Fig. 4, a side elevation of the same looking in the direction indicated by the arrow *z*, Fig. 3; Fig. 5, a side elevation of thread-guide and 45 contact-wheel; Fig. 6, a perspective view of the lock-plate for the former.

The main elements of the machine are the same as those shown in the patent above referred to.

Referring to Figs. 1 and 2, *b* is the winding spindle adapted to rotate in bearings 50 in the frame *c* of the machine and preferably tapered throughout its length extending outward from the frame to adapt it to receive the cop tube *x*, represented by dot-

and-dash lines in Fig. 1. The spindle *b* 55 is driven from the main driving shaft *d* of the machine through suitable connections such, for instance, as the spiral gears *e* and *f*. The main portion of the traverse-bar *g* is arranged to reciprocate on a line parallel 60 to the axis of the winding spindle and is driven from a rocker-arm *h* which is held by suitable clutch-devices on the oscillating shaft *i*. The main portion of the traverse-bar *g* slides in a bearing *j* secured to the 65 frame *c* and is connected to the rocker-arm *h* by a link *k*. The rocker-arm *h* has a plurality of holes *l*, *l*, etc. arranged at varying distances from the axis of the shaft *i* to provide for connecting the link *k* at different 70 points on the arm to vary the effect of the throw of the latter and change the extent of reciprocation of the traverse-bar.

The traverse-bar which carries the thread-guide is made in two sections, the main portion *g* being adapted to reciprocate in a straight line parallel to the axis of the winding spindle, as before explained, and the part *m* connected to the main portion by a pin and slot arrangement which allows 75 the inner end of the bar *m* to be moved laterally toward the winding spindle. The outer end of the bar *m* slides in a bushing *n* which is swiveled in an outboard bearing *o* fastened to the end of an outrigger bracket 80 *p* secured to the main frame, see Figs. 1 and 2. Referring to Fig. 1, the bushing *n* has an annular enlargement *n'* fitted to the bore *o'* of the bearing *o*. This allows the bushing to swing in the bore and a stud *o''* 85 is screwed into the bushing with its end engaging a hole in the bearing *o* to retain the bushing from displacement.

Mounted on the traverse-bar extension *m* is the thread-guide-holder *r*, of bifurcated 95 form with two legs *r'*, *r''*, the extremities of which surround the bar to form bearings thereon. The opposite end of the thread-guide-holder is adapted to receive and hold the thread-guide *s* which is formed with 100 the usual slot *s'*, serving as a passage for the thread or yarn *y*. The arrangement of the bearings of the thread-guide-holder on the traverse-bar allows the thread-guide *s* to oscillate to and from the winding spindle 105 to adapt it to follow the taper of the winding on the nose of the cop. The bar *m* is formed with partial screw threads *m'* cut

into the surface eccentric to its axis, see Fig. 5. Located between the two legs r' , r'' of the thread-guide-holder r is a nut t having its bore internally threaded, but of sufficient diameter to slide freely over the threads on the bar m when concentric with the latter. Secured to the nut t is a disk or wheel u which has been termed the progression or contact wheel because it acts to contact with the rotating cop to turn the nut t and feed the thread-guide-holder along the traverse-bar. As before stated, the nut t is free to slide over the threads on the traverse-bar when concentric with the bar, but to maintain the nut normally in engagement with the threads m' I provide a spring v secured to the thread-guide-holder r and arranged with its free end bearing on a flange u' on the wheel u . During the winding, when the thread-guide s bears against the cop, as shown in Fig. 5, the effect of the spring v will be to keep the nut t engaged with the threads on the bar m , but by swinging the thread-guide-holder r upward this effect of the spring v will be annulled and the nut will return to a position concentric with the bar. In this way the nut can be disengaged from the threads on the traverse-bar so that the thread-guide 30 may be returned to its initial position at the end of the spindle, after one cop is completed, to start the winding of a new cop. The means for maintaining the periphery of the progression wheel u in close proximity to the winding spindle at the beginning of the winding, to build the formation cone or heel of the cop on which subsequent layers are wound, is similar in general respects to that described in the patent before referred to and will next be explained.

As before stated, the two adjacent ends of the sections g and m of the traverse-bar are joined with a pin-and-slot connection. The end of the bar g is slotted at g^2 and also bored with the transverse hole g^3 , see Figs. 3 and 4. Inserted in the slot g^2 is a plate 2 formed with a portion which abuts the back 3 of the slot g^2 . A pin 4 is driven down through the rod and the plate to secure the latter in its position in the slot g^2 and the portion which abuts the back of the slot acts to steady the plate to prevent play. A slot 5 is provided in the plate 2, extending perpendicular to the rod g . The end of the rod m is also slotted at m^3 to receive the plate 2 and drilled with a transverse hole through which the pin or wire 6 projects down into the slot 5. The opposite end of the wire 6 is preferably coiled partly around the rod at 7 to hold the pin in place. The outer edge of the plate 2 is formed as a cam face 8 arranged at an angle to the axis of the rod g . The end of the rod m has an axial bore m^3 and a plunger 9 is fitted to slide therein with its end adapted to bear

on the cam face 8. The plunger 9 is turned down throughout a portion of its length to form the shoulder 10 and surrounding this reduced portion is a coiled spring 11. The spring 11 is held under tension between the end of the bore m^3 and the shoulder 10 and acts to force the end of the plunger against the cam face 8. Preferably, this end is slightly rounded to adapt it to slide smoothly on the cam. The effect of this arrangement is to normally maintain the bar m in axial alignment with the bar g , as illustrated by dotted lines, Fig. 3, with the pin 6 at the back end of the slot 5. The rear end of the bar m can be swung in toward the winding spindle against the action of the spring pressed plunger on the cam, as shown in Fig. 1, but when the lateral pressure at the end of the bar is released the plunger 9 acts on the incline of the cam 8 to return the bar to its normal position.

The means for swinging the end of the bar m toward the winding spindle consists of a guide or former 12 having an extension 14 adapted to bear on a follower arm 13 which may be formed as a part of the thread-guide-holder r or attached thereto. As here shown I have preferred to construct the arm 13 as an extension of the yoke 27 which is mounted on the traverse-bar m with its bearing legs 28 and 29 straddling the thread-guide-holder r to adapt the yoke to move with the latter along the bar, see Figs. 1 and 2. Referring to Fig. 5, a tongue 26 on the bearing 28 of the yoke 27 projects into a longitudinal slot 31 in the bar m to keep the yoke from turning on the bar and maintain the arm 13 of the yoke in position to bear on the arm 14 of the former 12.

In the patent previously referred to the former 12 is shown attached to the end of the bar g in a manner to allow the arm 14 being adjusted toward or away from the winding spindle, but no provision is made for changing the angle of the arm. The arm 14 is adjusted laterally in relation to the winding spindle to adapt the machine to wind cops of different diameters on different sizes of tubes. When cops of different diameters are wound either on the same or different diameters of tubes different sizes of contact wheels are used, and in order to set the wheel with its periphery close to the winding-spindle at the start of the winding the arm 14 must be adjusted in relation to the spindle. It has also been found desirable to change the angle of the former arm in some instances for different classes of materials. In winding relatively coarse yarns of cotton or other soft material the coils have a considerable inherent clinging tendency and are not easily displaced so that the cops can be wound with a comparatively steep taper or blunt nose. With hard or fine yarns such as silk or linen, however, the coils

of winding are more apt to slip or become displaced and therefore the cops cannot be wound with such a steep taper but must be built with a relatively sharp nose. It will be obvious that the angle of the former arm 14 regulates the taper of the heel of the cop or the formation of the ends of the layers of winding which overlap each other at their opposite ends to form the conical nose. It will therefore be seen that the taper of the heel of the cop controls the taper of the nose and consequently the latter can be regulated by changing the angle of the former arm in relation to the axis of the winding spindle. It has been found in practice that material change in the taper of the cop is not often required, but when such a change is necessary the adjustment must be made very carefully and precisely by a competent person in order to secure the best results. The ordinary operator is usually not enough skilled in the winding art to know the right degree of taper for different classes of material and therefore it has been found expedient to arrange the device so that under ordinary conditions the angle of the former arm will not be materially changed in changing its lateral relation to the winding spindle. With this object in view I have devised an arrangement whereby the arm 14 can be adjusted laterally in relation to the winding spindle under ordinary conditions without altering its angle of inclination to any great extent; and whereby in addition a skilled mechanic familiar with the machine can by changing certain parts of the mechanism adapt the arm to further adjustment to alter its angle of inclination materially in relation to the axis of the spindle. These devices for providing the adjustments described and for normally locking the arm against one of the adjustments form the essence of the present invention and will now be described.

As before explained, the former 12 is secured to the end of the section *g* of the traverse-bar which projects from the bearing *j* on the frame *c* of the machine. The plate 2 at the end of the bar *g* is formed with an extension 15 projecting at right angles to the axis of the bar and the former 12 is fastened thereto by the means now described. The inner end of the former 12 has a slot 16 through which the pin 4 at the end of the bar *g* projects and a second slot 17 is provided adjacent the arm 14. The extension 15 of the plate 2 is also formed with a laterally extending arcuate slot 18. A screw 19 having a washer 20 under its head extends down through the slots 17 and 18 with its end adapted to screw into a lock-plate 21, the latter shown in detail in Fig. 6. Referring to Fig. 4, the lock-plate 21 is provided with a hole 22 at one end adapted to receive a pin 23 projecting from the under

side of the plate 2. At the opposite end of the plate 21 is a pin 24 adapted to enter a hole 25 in the extension 15 of the plate 2 to retain the plate from turning on the pin 23. Between the pin 24 and hole 22 is the threaded hole 30 for receiving the end of the screw 19.

For usual conditions of winding the machine is assembled with the lock-plate 21 arranged with one end held by the pin 23 and the opposite end by the pin 24 projecting up into the hole 25. This brings the hole 30 in a position substantially midway of the length of the slot 18, as illustrated in Fig. 1. The former 12 is attached by placing it on top of the extension 15 of the plate 2 with the pin 4 projecting up through the slot 16 and the screw 19 screwed down through the slot 17 into the lock-plate 21. It will be seen that since the lock-plate 21 is held from lateral displacement by the two pins 23 and 24 the screw 19 will be restrained from movement in the slot 18 so that the former cannot be swung about the axis of the pin 4 to change its angular position in relation to the winding-spindle. By loosening the screw 19 the former can be adjusted laterally in relation to the spindle by sliding it on the pin 4 and screw 19, the slots 16 and 17 being provided to allow such an adjustment. In the Wardwell patent previously referred to the slots in the former 12 are shown in alinement so that lateral adjustment of the former arm is in a straight line. It will be noted that in the present showing, however, the slots 16 and 17 are not in exact alinement but have a slight inclination one to the other. This arrangement of the slots results in causing a slight change in the inclination of the former arm as the former 12 is moved from one extreme of position to the other, but this change is almost negligible. Its purpose is to vary very slightly the form of the heel and nose of the cop in accordance with changes in diameter of the latter for certain reasons. These slight changes need not be considered further, however, since they are not related to the prime purpose of the present invention. In fact, the operation of my new device would be the same if the two slots were arranged in alinement as in the patent previously referred to. The essence of my new improvement resides in the device which provides for a liberal adjustment of the former arm for changing from one extreme of taper to the other irrespective of the lateral displacement of the former.

In order to make this last mentioned change in the angle of the former it is necessary to first remove the screw 19 and release the lock-plate pin 24 from engagement with the hole 25 in the extension 15 of the plate 2. The lock-plate 21 is then turned with its

other side up against the extension 15, as shown in Fig. 4. In this position the pin 24 projects downward so that it is away from the hole 25 and when the screw 19 is replaced 5 it can be moved back and forth in the slot 18 with the lock-plate pivoting on the pin 23. In other words, the lock-plate when in the position illustrated in Fig. 4 is not restrained from lateral movement at its outer 10 end and hence when the screw 19 is loosened slightly the former 12 can be swung about the pin 4 as a pivot with the screw sliding in the slot 18. In this way a material angular adjustment of the arm 14 is provided for in whatever position the arm may 15 be in lateral relation to the spindle, so that almost any degree of taper, within certain limits, can be given to the ends of the cop.

It will be seen that my improvement 20 provides a practically fool-proof device which prevents inexperienced operators from tampering with adjustments which must be made very accurately by those skilled in the art. While the mechanism allows the operator 25 to make adjustments which are obvious and dependent on fixed conditions, only one having intimate knowledge of the machine and therefore particularly competent can make the fine adjustments which 30 must be based on good judgment and long experience. In other words, the ordinary operator from an examination of the machine will not become cognizant of the fact that the device can be set for a wide range of 35 angular adjustment of the former arm and hence he is prevented from making changes that can only be advisable under certain conditions. When such changes are necessary the machine expert or other skilled 40 workman can, by simply reversing the position of one element, adapt the mechanism to be adjusted as required.

Without limiting myself to the precise 45 form and arrangement of the parts shown, what I claim is:—

1. In a winding machine, the combination with a winding spindle and thread-guide, of means to cause a relative reciprocation between the guide and spindle, means engageable with the cop to feed the guide progressively along the spindle from beginning to end of the winding, said means being movable laterally away from the spindle to shape the base of the cop, a former for guiding 50 said means in its movement away from the spindle, means to adjust said former in angular relation to the spindle to regulate the taper of the base of the cop, and means to normally lock said former to prevent such 55 adjustment.

2. In a winding machine, the combination with a winding spindle and thread-guide, of means to cause a relative reciprocation between the guide and spindle, means adapted 60 to bear on the winding to feed the guide

progressively along the spindle, said means being movable laterally away from the spindle to shape the base of the cop, a former for guiding said means in its movement away from the spindle, means to adjust the former in angular relation to the spindle, and means reversible in position to either prevent or allow said adjustment of the former. 70

3. In a winding machine, the combination 75 with a winding spindle and thread-guide, of means to cause a relative reciprocation between the guide and spindle, means adapted to bear on the winding to feed the guide progressively along the spindle, said means being movable laterally away from the spindle to shape the base of the cop, a former for guiding said means in its movement away from the spindle, said former adjustable laterally in relation to the spindle and 80 also in angular relation thereto, and means to normally lock the former against angular adjustment while allowing lateral adjustment. 85

4. In a winding machine, the combination 90 of a rotating spindle, a thread-guide, means to cause a relative reciprocation between the spindle and thread-guide, a progression wheel arranged to travel in a path inclined to the axis of the spindle, means operated 95 by said wheel to cause a relative advance of the guide along the spindle, a former to guide the movement of the wheel, said former adapted to be adjusted laterally and angularly in relation to the spindle, and means to normally prevent angular adjustment 100 of the former, said means shiftable to allow such adjustment. 105

5. In a winding machine, the combination 110 with a winding-spindle, traverse-bar, and thread-guide, of means adapted to contact with the winding to feed the guide along the bar, a former for controlling the position of the contact means in relation to the winding-spindle at the start of the winding, 115 means to adjust said former laterally in relation to the spindle, means to adjust the former in angular relation to the spindle, and locking means to prevent angular adjustment of the former while allowing lateral adjustment of the same. 120

6. In a winding machine, the combination 125 with a winding-spindle, traverse-bar, thread-guide and contact-means adapted to be engaged by the winding to feed the guide along the bar, of a former-device adapted to press the contact means toward the winding-spindle at the start of the winding and having an angularly disposed arm adapted to guide the contact means as the latter recedes from the winding-spindle with the growth of the cop, means to adjust the former arm in lateral relation to the winding-spindle, means to change the angular 130 position of the arm, and a locking device to

normally prevent angular adjustment of the arm while allowing lateral adjustment.

7. In a winding spindle, the combination with a rotating spindle, a reciprocating traverse-bar, a thread-guide mounted on the bar, a wheel adapted to contact with the winding to feed the guide along the bar, of means to control the position of the wheel in lateral relation to the spindle as the winding increases in diameter including a former device having an arm arranged at an angle to the axis of the spindle, means to adjust the former arm in lateral relation to the spindle for different sizes of cops, means to adjust the former arm in angular relation to the spindle to change the shape of the cop, and means to normally lock said arm against angular adjustment without preventing lateral adjustment.

8. In a winding machine, the combination with a rotating spindle, a reciprocating traverse-bar, a thread-guide mounted on the bar, a wheel adapted to contact with the winding to feed the guide along the bar, means to swing the bar to bring the wheel in close proximity to the spindle during the winding of the first layers of the cop, said means having a former arm to guide the wheel away from the spindle to form the heel of the cop, means to adjust said arm in lateral relation to the spindle, means to adjust the arm in angular relation to the spindle, and locking means to normally prevent angular adjustment of the arm while allowing lateral adjustment.

9. In a winding machine, the combination of a winding-spindle, a thread-guide, a wheel adapted to contact with the winding to feed the guide progressively along the spindle and arranged to move away from the spindle with the growth of the cop, a former for guiding the movement of the wheel to regulate the shape of the cop, means to secure the former to allow its adjustment toward and away from the spindle in a substantially perpendicular direction, means to adapt the outer edge of the former to swing to adjust its angular position, and a lock plate which when arranged in one position allows the movement of the former toward and away from the spindle but prevents its swinging movement and when in the reverse position allows both adjustments.

10. In a winding machine, the combination with the winding-spindle and thread-guide, of a contact-wheel for feeding the guide along the spindle, a former for guiding the movement of the wheel in a path inclined to the axis of the winding-spindle, means to secure said former to allow its adjustment toward and away from the spindle, means to adapt the former to be swung to vary its angular position in relation to the spindle, and a lock-plate attachable in one position to prevent swinging movement of the former

while allowing straight-line movement and attachable in another position to allow both movements of the former.

11. In a winding machine, the combination with the winding-spindle and thread-guide, of means to feed the guide progressively along the spindle, a former for controlling the position of the guide-feeding means in relation to the spindle, a plate to which the former is attached, means to secure the former to said plate to adapt it to be adjusted laterally toward and away from the spindle and in angular relation thereto, and a lock-plate adapted to be attached to the plate to prevent angular adjustment of the former while allowing lateral adjustment, said lock-plate reversible in position to permit angular adjustment of the former.

12. In a winding machine, the combination with the winding-spindle and thread-guide, of means to feed the guide progressively along the spindle, a former for regulating the path of travel of the guide-feeding means in relation to the spindle, means for securing the former in position including a plate 2 formed with a transverse slot 18, a screw 19 extending through the former and the slot 18, a lock-plate 21 adapted to receive the threaded end of the screw, and means to secure the lock-plate to the plate 2 in such manner as to normally prevent movement of the screw 19 in the slot 18 or to permit said movement when it becomes necessary to change the angular position of the former.

13. In a winding-machine, the combination with the winding-spindle and thread-guide, of means to feed the guide progressively along the spindle, devices for controlling the path of travel of said guide-feeding means including a former 12 having a guiding arm 14 and slots 16 and 17, a plate 2 formed with a transverse slot 18, a pin engaging the slot 16 in the former 12, a screw 19 extending through the slots 17 and 18, a lock-plate 21 pivoted at one end on the plate 2 and having a hole 30 alining with the slot 18 and adapted to receive the end of the screw 19, and means adapted to secure the lock-plate from turning on its pivot to prevent the screw 19 from sliding in the slot 18 but releasable to allow said movement to adapt the former arm to be adjusted in angular position.

14. In a winding machine, the combination with the winding-spindle and thread-guide, of means to feed the guide progressively along the spindle, devices for regulating the position of said guide-feeding means with respect to the spindle including a former 12 having slots 16 and 17, a plate 2 having a transverse slot 18, a pin 4 projecting from the plate 2 to engage the slot 16, a screw 19 extending through the

slots 17 and 18, a lock-plate 21 having a hole 30 to receive the end of the screw 19, a pin 23 on the plate 2 engaging a hole at one end of the lock-plate 21, and a pin 25 at the opposite end of the lock-plate adapted to engage a hole in the plate 2 when the lock-plate is in its normal position but arranged to be out of range of the plate 2 when the position of the lock-plate is reversed.

15. In a winding machine, the combination with the winding-spindle and thread-guide, of means to cause a relative advance between the spindle and guide, a former for controlling the position of the guide-advancing means in relation to the spindle, means to secure the former in position to allow it to be adjusted laterally toward and away from the spindle and in angular relation thereto, and a lock-plate which in one position allows the former to be adjusted both laterally and angularly but in its reverse position prevents angular adjustment of the former.

25. 16. In a winding machine, the combination with the traverse-bar *g*, of a plate 2 secured to said bar and formed with an extension 15 having a transverse slot 18, a former 12 pivotally connected to said plate 2, a screw 19 extending through the former 12 and slot 18, and a lock-plate 21 adapted to receive the end of the screw 19 and arranged to be held against lateral movement on the plate 2 when in normal position but reversible in position to adapt

it to swing on the plate 2 to allow movement of the screw 19 in the slot 18.

17. In a winding machine, the combination with a traverse-bar having two sections with the section *g* arranged to reciprocate with a straight line movement and the section *m* adapted to swing laterally with respect to the section *g*, means to connect the adjacent ends of the two sections, a former 12 secured to the end of the section *g* in position to control the swinging movement of the section *m*, means to adjust the former in a line substantially perpendicular to the section *g*, means to adjust the former in angular relation to the axis of the section *g*, and a lock-plate 21 adapted to normally secure the former against angular adjustment.

18. In a winding machine, the combination with the traverse-bar, of a plate secured at the end of said bar, a former slideable on said plate and adapted to swing thereon to vary its angular position in relation to the traverse-bar, and means to normally restrain the former from swinging movement while allowing it to slide on the plate to adjust it in lateral relation to the bar.

In testimony whereof I affix my signature in presence of two witnesses.
